(57) **CLAIM**

I claim the ornamental design for a bottle with dispensing cap, substantially as shown and described.

DESCRIPTION

FIG. 1 is a perspective view of a bottle with dispensing cap showing the new design;

FIG. 2 is a front view of a bottle with dispensing cap showing the new design;

FIG. 3 is a left side view of a bottle with dispensing cap showing the new design;

FIG. 4 is a right side view of a bottle with dispensing cap showing the new design;

FIG. 5 is a rear view of a bottle with dispensing cap showing the new design; and,

FIG. 6 is a top view of a bottle with dispensing cap showing the new design.

The broken lines in the drawings illustrate the portions of the bottle with dispensing cap that form no part of the claimed design.
